Paper Manufacture

Paper Hangings.

EX

OF 0 13,274

UNITED STATES PATENT OFFICE.

EDUARD LEISSNER, OF NEW YORK, N. Y.

DESIGN FOR WALL-PAPER.

SPECIFICATION forming part of Design No. 13,274, dated August 29, 1862.

Application filed June 30, 1862. Term of patent 3½ years.

To all whom it may concern:

Be it known that I, EDUARD LEISSNER, of New York, in the county and State of New York, have invented a new and original Design for Wall-Paper and Similar Fabrics, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

A is a figure composed of a net-work or cord-work, in which are fastened rosettes of various sizes and shapes, and around one edge of which extends a fringe, b, while beyond this fringe the net-work is continued, also bearing

rosettes, one of which, c, is considerably larger than the others, and beyond this net-work extend a series of loops, having ball-like fringe therein, and joining the figure A to the figure a. The figure a consists of several acorn-like pendent figures held by the surrounding net-work. The whole effect of the design is that of an interlacing net-work supporting the fringes and figures described, which are repeated in regular succession.

I claim—

The design for a wall-paper, consisting of the figures A, a, b, and c, substantially as shown.

EDUARD LEISSNER.
